PHONOGRAPH APPARATUS

Matthew H. Loughridge, Bogota, N. J.

Continuation of application Serial No. 285,724,
June 15, 1928. This application November 28,
1928, Serial No. 322,534

56 Claims. (Cl. 274—10)

This invention relates to phonograph apparatus and has for an object to obtain a universal phonograph which may be used for duplicating records from a master, repeating in continuation 5 a series of records, selectively playing any one of a number of records, and changing the records on the machine without stopping or disturbing its operation. The mechanism whereby these results are obtained includes means for driving 10 a plurality of turntables in synchronism from a driving shaft, means for disconnecting any turntable from the driving shaft, means for starting the turntable and accelerating its speed before it is connected with the driving shaft and means 15 whereby the turntable is brought into engagement with the driving shaft with a cushioned engagement. The mechanism further includes a feeding mechanism with a sliding carriage in which is embodied an electric responsive device 20 for controlling the operation of the machine, also a mechanism controlled by a micrometer adjustment for starting the stylus at the proper groove in the record and for stopping the stylus when the record is completed and starting the feed mechanism of a following record. The mechanism further includes means for adjusting the speed at 25 which the turntable may be driven by the driving shaft, means for preventing the stylus from recording sound until it is in engagement with the record groove, means for manually resetting the feed mechanism on each turntable simultaneously and means for automatically resetting the feed mechanism. Other objects of the invention 30 are described in detail in the following specification and are illustrated in the accompanying drawings, selected to show a preferred form of my invention.

In the drawings, Fig. 1 is a side elevation of a phonograph mechanism constructed according to 40 this invention, Fig. 2 is a rear elevation corresponding to Fig. 1; Fig. 3 is an enlarged plan view, partly in section of one turntable mechanism, Fig. 4 is an elevation corresponding to Fig. 3, Fig. 5 is a detail, partly sectioned, looking towards the right 45 in Fig. 3, and Fig. 6 is a detail of the self-starting gear. Fig. 6a is a detail showing the ratchet mounting for the turntable drive.

Fig. 7 is an elevation of the feeding mechanism and Fig. 8 is a side elevation of a modified form of 50 the feeding mechanism, Fig. 9 is a detail showing the transverse adjustment of the stylus head and Fig. 10 is a view, partly sectioned, showing the friction drive for the turntables.

Fig. 11 is a controlling circuit from the magnetic pick-up of the turntables, through an am-

plifier to a loud speaker, Fig. 12 is a controlling circuit used when records are to be repeated in continuation and Fig. 13 is a circuit that may be used when records are selectively played.

This invention is a continuation of my co-pending application, Serial No. 285,724, filed June 15, 1928, now Patent 1,877,625, dated September 13, 1932, also the corresponding British Patent 331,339, of 1930.

This invention comprises a pair of standards 10 supporting a plurality of turntable brackets spaced one above the other and a vertical driving shaft with friction wheels arranged to engage the edges of the turntables whereby the latter are driven in synchronism and a feeding mechanism 15 driven from the driving shaft operates the stylus across the turntable, which, through a magnetic pick-up and suitable amplifying means plays the record. When the machine is used as a recording outfit to make duplicates from a master, the 20 master record is placed upon one of the turntables and the records to be inscribed are placed upon the other turntables. The feeding mechanism for each record is simultaneously operated and by suitably connecting the magnetic pick-up 25 of the master record with the magnetic recording heads of the duplicates, through an amplifying circuit, duplicates of the master record are easily and quickly produced.

When the machine is used for playing in continuation, a series of records which may be a continuation of the same subject, or may be individual records, the electric control of the feeding mechanism is used to insure that only one record may be played at a time and to insure that 30 the records will start playing at the proper time and end at the proper time. For this purpose a micrometer adjustment is associated with the feed mechanism which enables the stylus to be set for the starting groove in various sized records 35 and changes the controlling circuits when the record is finished so that the following record may be started at the proper instant to produce a continuation of the subject. When the records are synchronized with another device, such, for 40 example as a motion picture projector, it may be necessary that the stylus be brought into action with reference to the angular position of the turntable so that the sound may be started, say within 45 sixty degrees of movement of the record groove and for this purpose a circuit is controlled by the turntable affecting the feed mechanism. When records are to be played selectively, as in a coin 50 controlled machine, a selector switch is provided whereby the desired feed mechanisms may be 55

brought into operation. This feed mechanism not only carries the stylus across the record when playing but automatically restores the stylus to the starting position when the record has been 5 played.

The stylus head is automatically raised from engagement with the record by the feed mechanism. When this mechanism is disengaged from the feed screw the stylus head is raised through a 10 lost motion connection and held free of the record. A circuit is controlled by the preliminary movement of this mechanism as it is disengaged from the feed screw which interrupts the circuit of the stylus head and thereby avoids the "click" 15 which usually accompanies the placing and removal of the stylus head on the record.

As the machine consists of a number of turntables which may be rotated in synchronism, it is desirable to be able to disconnect any turntable 20 from the driving mechanism so that records thereon may be changed without stopping the operation of the machine. It is also necessary that after a turntable is stopped, it may be connected to the drive without disturbing or varying the 25 speed of the driving mechanism. For this purpose the turntable is mounted on a swinging arm which is, by the tension of a spring, moved to the position to bring the turntable into engagement with the driving wheel. This spring operates 30 through a dash pot controlled by air escaping from a restricted orifice so that the initial engagement between the turntable and the drive is controlled by an air cushion. The stem of the turntable is provided with a gear which meshes with 35 a fixed arm as the turntable is moved towards the driving position. This gives the turntable an initial impetus and operates as a self starting mechanism which speeds up the turntable in the same direction in which it is driven so that it 40 engages the driving wheel at a speed that is approximately in synchronism therewith and immediately resumes synchronous speed without introducing any retarding effect on the driving mechanism. The additional load of rotating a 45 turntable brought into circuit in this way is applied with a graduated action through the spring and dash pot. The self-starting gear on the stem of the turntable is mounted on a ratchet so that it does not affect the movement of the turntable 50 when the latter is released from the driving mechanism.

The change-over from one record to the following record is effected through the feed mechanism which co-operatively connects to the feed 55 screw and brings the stylus into engagement with the record. This may be adjusted so that the last groove of one record is played at the same time as the first groove of the following record. The machine may be used in the same way for recording a subject continued from one record to another.

In the drawings 11 is the base casting which supports the pipe standards 13 and 14 and the motor 12. The vertical drive shaft 15 connects 60 by the worm wheel 16 and worm 17 with the motor 12 and is constantly rotated by the motor, preferably at a regulated speed. Turntable brackets 18 are secured to the pipe standards 13 and 14 and any number may be arranged in vertical tiers as 65 at A, B, and C. At each turntable bracket the shaft 15 is provided with a friction wheel 19 which normally engages the edge of the turntable 20 and thus the turntable on each bracket is rotated by the motor 12.

75 The bracket is developed into a horizontal arm

21 which terminates in the jaw 22—23, Fig. 5 and to this jaw the swinging arm 24 is pivoted at 25. This swinging arm supports the turntable, the stem of which is indicated at 26. A projection 27 extends as shown, from the lower 5 member 24 of the swinging arm and is pivotally connected with the plunger 28 which terminates in the piston 29 in cylinder 30. The coil spring 31 normally projects 28 until the turntable engages the friction wheel 19 in the position indicated by a and maintains a constant pressure between the turntable and the friction wheel. The piston 29 acts as a dash pot to secure a graduated engagement between the turntable and friction drive as the air escapes from the 15 cylinder 30 through an orifice regulated by screw 32. A cam 33, pivoted at 34 and operated by handle 35 engages projection 27 and moves the turntable to the position b by swinging 24 to the position c. The turntable is thus disconnected 20 from the drive, or is connected to the drive as desired by manipulating handle 35. It is apparent that results corresponding to the swinging arm 24 can be obtained by a variety of equivalents.

The stem of the turntable 26 is provided with the spur gear 38 which meshes with the gear teeth 37 in the extended portion 36 of jaw 22 as the arm 24 is swung into and out of the engaging position. It will be noted that in each 30 of the extreme positions of arm 24, the gear 38 is clear of 37 and rotates free thereof. As arm 24 is swung to the right to bring the turntable to position a the stem 26 is rotated by the engagement of gear 38 with the fixed part 36. 35 This starts the turntable and causes it to rotate at a speed which can be regulated by the dash pot and may be made to approximate the corresponding speed of the friction wheel 19 so that as a turntable is brought into circuit there is 40 no disturbance in the drive. It will be noted from Fig. 6 that the spur gear 38 is mounted on a ball ratchet 39 in the central part of the gear which connects to the turntable to drive the turntable when 38 engages 37 moving towards 45 the right, but when 38 engages 37 moving towards the left, or from the position a to the position b, the ratchet is released and the turntable is not rotated thereby. The central part of gear 38 is mounted on and rotates with the 50 turntable stem 26. In the figure, parts of the cover are removed to show the ball ratchet. This ratchet construction is necessary as without it the gear 38 would tend to rotate the turntable in the opposite direction to the driven direction 55 as it is moved to the released position.

It will be observed from Fig. 5 that underneath the turntable 20 the disc 40 is mounted on stem 26 through the insulation 41 so that it rotates with but is electrically insulated from 60 the turntable. A bracket 43 is secured to arm 24 and supports the insulated contact fingers 42 which engage the edge of disc 40 and thus controls a circuit by the rotation of the turntable as hereinafter described.

65 The feeding mechanism is used to feed the stylus across the record. It comprises the feed screw 53 mounted in the supports 54 and 55 and carrying the spiral gear 52 which meshes with gear 51 on the drive shaft 15. By this arrangement the feed screw is continuously rotated when the machine is running. A sliding bar 56, parallel to the feed screw 53 is mounted on the supports 58 and 59. This bar is non-turning and is splined at 61. A carriage 60 is mounted 70

on this bar that can slide freely on the bar but engages the spline 57 so that it is non-turning. Rigidly mounted on 60 is the carriage head 61 which supports the electro-magnet 67. Loosely mounted on 60 is the feed arm 63 which, by gravity in the construction in Fig. 7, engages the feed screw 53 and is provided with the armature 68 so that when magnet 67 is energized the feed arm 63 is raised and disengaged from the feed screw and the feeding mechanism is thereby rendered inoperative. When 67 is deenergized the feed arm resumes its engagement with the feed screw and the feeding mechanism becomes operative.

15 Loosely mounted for rotation on carriage 60 is the stylus arm 64 which supports the rod 65 and the stylus head 66. Thus the stylus head by gravity engages the turntable record and is moved transversely over the turntable as the 20 carriage 60 is moved by the feed arm on the slide 56.

It is necessary that the stylus be raised from the record when the feeding mechanism is inoperative. For this purpose a lug is formed integral with the feed arm at 69, Fig. 7 which is linked at 70 to the lever 71 pivoted at 72 to the carriage 61 and connected by rod 73 and pivot 74 with the stylus arm 64. The connections are so arranged that by raising 63 the stylus 30 head is raised from the record and by lowering 63 the stylus is lowered to engage the record. It will be observed that the lost motion in link 70 permits the stylus arm to be raised independently of the movement of 63.

35 It is desirable that the stylus head be raised from the record when the turntable is moved out of engagement with the driving mechanism and automatic means are provided for this purpose comprising the rod 71 passing below 65 and supported by arms 75 and 76 pivotally mounted on bar 56. This rod connects by 78, Fig. 4, with crank 79 and by connection 80 with the crank 81 on the end of handle 35, Fig. 5. Thus, as 40 handle 35 is moved to disengage the turntable from the drive the stylus head is disengaged from the turntable by the preliminary movement of the handle.

When the machine is used for duplicating purposes with all the turntables operating at the 50 same time, it is desirable to be able to reset all the feeding mechanisms simultaneously and to bring them into operation simultaneously. For this purpose the rod 85 is provided sliding in the head 83 and having a dog at 86 which engages the projection 87 of the feed arm. The head 83 is hinged at 84 to the bracket 82 which is clamped to the standard 13. The vertical rod 88 connects the horizontal rods 85 as shown so that an upward movement of this rod raises all the 55 heads 83, rods 85 and feed arms 63 and an outward movement of 88 restores all the feeding mechanisms to the starting position.

It will be noted that by raising rod 88 all the 60 feed mechanisms are simultaneously disconnected and by lowering this rod they are simultaneously placed in condition for operation. When the feeding mechanisms are restored to the starting position the rods 85 are restored to the position indicated in Fig. 3 so as not to interfere with 65 the normal operation of the mechanism.

The feeding mechanism in Fig. 8 is substantially similar to the mechanism in Fig. 7 with similar parts correspondingly referenced. This arrangement, however, is modified to bring the 70 feeding mechanism into operation when the mag-

net 67a is energized instead of when this magnet is deenergized. It will be noted that the feed arm 63a engages the underside of feed screw 53 and is held in engagement therewith as long as armature 68 is attracted by magnet 67a. When 5 magnet 67a is deenergized the feed arm 63a by gravity, engages reverse screw 106 which is geared to screw 53 by spur gears 107 and 108. The result therefore is to feed the stylus across the turntable when magnet 67a is energized and 10 to raise the stylus from the turntable and return the feed mechanism to the starting position when magnet 67a is deenergized. It will be noted that the link 70 connects to lever 71 on the opposite side of pivot 72 from the construction in Fig. 7 15 to insure the lifting of the stylus head when the feed arm is disengaged from the feed screw.

In the centre of carriage 60 is a non-turning member 62, Fig. 3, which is keyed to carriage 60 and is used to support the circuit controller 62a, 20 Figs. 7 and 8, which is operated by the movement of the feed arm in response to magnet 67. The long contact springs of 62a and 62b are connected with 63 by a block of insulation as shown and move therewith to establish circuit connections as indicated in Fig. 11, after the stylus head is in engagement with the record. Also a circuit controller 138, Fig. 3 is provided to interrupt a circuit by engagement with carriage 61 on the return of the feed mechanism to the starting 30 position, as hereinafter described.

Phonograph records usually vary in size so that the sound grooves end at various positions of the feed mechanism and it is desirable to disconnect the feed mechanism and raise the stylus 35 from the record when the last sound groove has been reproduced. For this purpose a mechanism controlling the circuit of magnet 67 is provided and operated by the feed mechanism through a micrometer adjustment which can be adjusted 40 with precision to control the operation of the feed mechanism and the operation of the feed mechanism for the following record, at any predetermined position desired.

The support 93 is rigidly mounted on bar 56 45 and has the lever 94 pivoted thereto at 95 and biased to move in a predetermined direction by spring 96. The plunger 91 is engaged by carriage 60 and is adjustably connected by the screw with stem 92 which slides in 93 and engages lever 94 50 to move it in opposition to spring 96. The arm 97 supports the contact plate 99 through the pivot 98. The contact plate carries the insulated stop screws 100 and 101 between which the contact member 102 moves in response to plunger 91 and spring 96. In operation, the stylus is placed at the end of the sound groove of the record and plunger 91 is then adjusted to engage the carriage so that the continued movement of 55 the carriage moves the contact 102 out of engagement with screw 100 and into engagement with screw 101. A fine adjustment may be obtained in the position of these contacts relative to 102 by the screw 103 engaging the projection 104 of the plate 99 and moving it on its pivot 98 against the flat spring 105. By this arrangement the feed mechanism may be disconnected in less than 60 one turn of the turntable.

It is necessary in some cases to be able to adjust the position of the stylus relative to the starting groove of the record independently of the feed mechanism. For this purpose the construction in Fig. 9 may be used. The supporting rod 65 is pivoted at 48 to swing horizontally in the arm 64 and has a projection 46 engaging spring 75

45 on one side and opposed by the adjusting screw 47 on the other side. By operating screw 47 the position of the stylus is adjusted independently of carriage 60.

5 In the apparatus disclosed, a feed mechanism in the form of a lead screw is provided which carries the arm supporting the stylus head across the record at the same time as the stylus is carried across the record by the spiral sound grooves.

10 Other types of phonographs are used having what is known as "the free tone arm", in which the spiral sound grooves feed the stylus as the turntable rotates and in which there is no special mechanism for moving the supporting arm laterally over the record, in the usual construction it is pivoted and balanced and moves on its pivot with the stylus head. In this apparatus, the turntables are maintained in continuous rotation and the records on the turntables are prevented from

15 playing by holding the stylus head released from the sound grooves of the record and the feeding action of these sound grooves. The feeding mechanism, as herein referred to and except when associated with structural limitations, includes 20 the feeding by the spiral sound grooves as well as the feed screw arrangement of the drawings.

A friction drive is preferred in the present machine for operating the turntables and where absolute synchronism is desired it is necessary that 30 adjustment be provided in the drive ratio. One way of securing this result is illustrated in Fig. 10 in which the drive shaft 15 is threaded and splined at 111. The friction wheel 19 is secured between a pair of plates 112 and 113 which slide on the threaded shaft but engage the spline 111 making a non-turning engagement with the shaft 15. This construction is held in place by the clamping nuts 114. It will be noticed that the wheel 19 is conical in shape and the turntable 20 is correspondingly 40 coned in the reverse direction as indicated at 115 so that the engaging circumference of these members can be adjusted by adjusting the position of 19 on the shaft 15. This enables the drive ratio between 19 and 20 to be adjusted with precision.

45 It will be noted that the gear wheel 19a is larger in diameter than 19 so that turntable 20a rotates at a higher speed than turntable 20. This has a certain advantage in duplicating work where the master record may be run at a higher speed than the duplicates. This has the effect of condensing the sound grooves on the duplicates which can be reproduced at a correspondingly lower speed and a small record has the same effective area as a large record. This arrangement is 55 highly practical with metallic records.

Another modified form of drive is shown in Fig. 10 which varies the speed of one turntable relative to another. The friction wheel 19b is 60 comparatively wide and cone shaped to engage turntable 20b. Wheel 19b slides in spline 111 and is moved by bar 171 sliding in guides 172 and engaging the wheel between collars 114-114a. By moving bar 175, the cams 173-174 are rotated on bearings 176 to lift bar 171 against spring 177 and thus change the speed of turntable 20b as desired.

Fig. 11 illustrates one arrangement of circuits that may be used to control the electric reproducers so that one reproducer will be operative at a time. The stylus heads 66 for the turntables A, B and C are connected by wire 123 with the 70 amplifier 121 and each of these heads is connected by wires 124 with the circuit controllers 62a and from these circuit controllers by wire 125 to amplifier 121. The dynamic current produced by

the movement of the stylus on the record is amplified by 121 and reproduced through the loud speaker 122. The circuit controller 62a is operated by the feed arm 63 closing the circuit only when the feed arm is in engagement with the feed screw. The circuit of the stylus head is thus disconnected except when the stylus is actually engaging the sound groove of the record, and as this circuit is open during the preliminary movement of the stylus head on the record no false sound can be transmitted by the engagement of the stylus with the record.

The controlling circuits in Fig. 12 are used where records are to be played, one succeeding the other on each of the turntables and, if desired, after the series of records have been played, the machine will automatically start with the first record, after the last one is completed and repeat the records in series indefinitely. The circuit arrangement for each turntable A, B and 20 C are similar and, as shown, the record on turntable B is being played as the magnet 67 for this turntable is deenergized while the magnets 67 for each of turntables A and B are energized and therefore the mechanism is inoperative.

25 Magnet 67 is energized from battery 126 by switch 126a and wire 128, also by wire 130, wire 132, contact finger 133 of relay 135 in the energized position and wire 127 to battery. After magnet 67 is energized a holding circuit is established through contact 62b closed by the feed arm 63 in the raised position, through wire 129 and contacts 42 engaging the disc 40 and wire 127 to battery. The disc 40 may be provided with a non-conducting segment 131 which interrupts the circuit between the contacts 42 for each revolution of the turntable.

30 By this circuit it will be noted that if magnet 67 is energized it remains energized until the turntable is in the predetermined position to interrupt the circuit at 42. Another holding circuit is provided on wire 129 through contact 100 and contact finger 102 to the battery wire 127. In this case contact finger 102 is controlled by the carriage of the preceding turntable so that until 45 this carriage reaches its final position, magnet 67 of the following turntable is held energized. On the other hand, when the preceding carriage has completed its movement, the finger 102 changes position opening the circuit of magnet 50 67 of the following turntable which is deenergized as soon as the circuit is interrupted at 42 and following this a circuit is established from wire 127, through 102 to contact 101 and wire 134 to relay 135 and by wire 128 to battery 126. 55 This energizes relay 135 and closes a holding circuit at 136 to wire 137, circuit controller 138 and wire 127 to battery. Relay 135 thus energized remains energized until the feed mechanism is restored to the starting position where 60 the carriage opens the circuit controller 138 and deenergizes 135 and opens the controlling circuit of 67 at 133. A switch 137a may be provided for manually deenergizing relay 135 without restoring the feed mechanism to the starting position. The energizing circuit of magnet 67 on wire 130 and the energizing circuit of relay 135 on wire 134, is known as the pick up circuit of these magnets. The circuit of the magnets controlled by their own armatures is known as the 65 stick or holding circuit.

In operation it will be noted that the contact finger 102 for turntable A has just been moved to the reverse position by the completed movement of the carriage and that carriage for turn- 70 75

table B is at the starting position with contact 138 open and relay 135 deenergized. This causes the deenergization of 67 for turntable B as soon as the circuit is interrupted at 42 and relay 135 for turntable A is energized, energizing magnet 67 for this turntable which remains energized until the carriage is returned to the starting position to open the circuit at 138, and until switch 102 of the preceding turntable is reversed.

10 The magnet 67 for turntable C is held energized through contact finger 102 for turntable B connecting wire 129 to battery wire 127. If switch 126b is closed it will be noted that magnet 67 for turntable A will be maintained energized 15 through wire 129, 129a, switch 126b, and contact finger 102 to battery wire 127. This arrangement insures that magnet 67, after it is energized at the completion of the movement of the carriage, is held energized until the preceding carriage 20 has completed its movement and set up the conditions for the operation of the following record. By closing switch 126b it will be noted that after the last turntable C has completed a movement of its carriage, the conditions are set up to start 25 the turntable A again and thus repeat the series again. It should be observed that when the holding circuit of magnet 67 is opened at 62b this magnet cannot be again energized on wire 129 and restoring the normal position of contact finger 102 by spring 96 does not affect magnet 67 until it is again energized by relay 135 being energized.

In the arrangement described the carriage may be manually restored to the starting position as 35 the records on the turntables are changed, or the carriage may be automatically restored by any of the arrangements used for this purpose.

In Fig. 13 a repeating and selective control is provided. The magnets 67a for each of the turntables cause the feed arm to engage the feed screw when these magnets are energized and to engage the return screw when these magnets are deenergized, as in Fig. 8. The main switch 142 closes the circuit from battery 141 through wires 45 143 and 144 to motor 12 and also closes the circuit to the selector 145. When the selector is in one position the circuit is closed from the battery 141 through switch 142, selector contact arm 155, wire 146, magnet 67a of turntable A and wire 143 50 to battery. When the selector is moved to another position, a circuit is established from 155 on wire 147 to magnet 67a for turntable B and when the selector is moved to another position a circuit is established on wire 148 for magnet 67a 55 for turntable C.

The selector 145 may be manually operated from some remote point to play any selected record. It may also be operated automatically to bring the controlling arm 155 progressively into 60 circuit with each of the controlling magnets 67a to play the entire series of records and to repeat the series as long as desired. For this purpose the selector arm 155 is stepped around by the magnet 151 operating the detent 152 engaging 65 the ratchet wheel 154 and producing one step each time magnet 151 is energized. Magnet 151 is controlled by battery 141, wire 141a, wire 166 and contact segment 165. Circuit controllers 138a are provided to be closed by the feed mechanism in its final movement for each of the respective turntables.

When 138a for turntable A is closed, a circuit is established from battery wire 143 by wire 161 to a contact in line with the insulated contact 70 plate 164 carried by arm 155 to bridge this con-

tact with 165 and thus energize the selector magnet 151 causing it to make one step of 154 thereby deenergizing magnet 67a for the last turntable played and energizing magnet 67a for the next turntable. When the feed mechanism of this 5 turntable completes its movement circuit controller 138a for this turntable establishes a circuit on wire 162 which, at this time, connects to 151 and again steps the selector around to play the next record. When the feed mechanism of 10 this turntable in turn, completes its movement, a circuit is established on wire 163 which now connects to magnet 151 thereby changing the selector to play the next record, and so on for any 15 number of turntables. As the feed screws are continuously rotating it will be noted that each feed mechanism is automatically restored to the starting position as soon as magnet 67a is deenergized.

It will be observed in Fig. 12 when switch 126a 20 is opened, all the controlling magnets 67 are deenergized and the feed mechanisms all operate simultaneously which is necessary for duplicating work. In Fig. 13 the same result obtains when 25 all the magnets 67a are energized.

The bevel gear 44 is provided on shaft 15 for connecting with a synchronizer which is not part of the present invention.

It is apparent that this invention may be constructed in a variety of forms embodying the 30 principles herein disclosed without departing from the intent and spirit of the invention.

Having thus described my invention, I claim:

1. In a phonograph, the combination, a driving shaft, a turntable, means for moving said turntable in one direction into frictional engagement with said driving shaft and for disengaging said turntable and drive shaft when moved in the opposite direction and means for automatically starting said turntable before it connects 40 with said shaft.

2. In a phonograph as described, the combination, a driving shaft, a turntable mounted on a swinging arm, means for connecting and disconnecting said turntable with said driving shaft by 45 swinging said arm in opposite directions and means including a ratchet for automatically starting said turntable by the movement of said swinging arm in the direction in which said connection is made.

3. In a phonograph, the combination, a driving shaft, a turntable having a stem with a gear thereon, means for moving said turntable to connect and disconnect with said driving shaft and means engaging with said gear to start said turntable before engaging with said driving shaft, said gear having a ratchet connection with said stem. 55

4. In a phonograph, the combination, a driving shaft, a turntable, means for connecting said turntable with said driving shaft by friction and 60 a spring and dash pot for controlling said connection.

5. In a phonograph, the combination, a driving shaft, a swinging arm, a turntable mounted on said swinging arm to swing in one direction 65 into the operating position and in the reverse direction to swing out of the operating position, means including said swinging arm for connecting said turntable with said driving shaft by friction, means for starting said turntable before 70 said connection is made and for releasing said turntable from the starting means when swung out of the operating position.

6. In a phonograph, the combination, a driving shaft, a turntable mounted on a swinging 75

- arm, means including said swinging arm for connecting said turntable with said driving shaft by friction and means for cushioning said connection.
- 5 7. In a phonograph, the combination, a driving shaft, a turntable, means for connecting and disconnecting said shaft and turntable, a stylus head connected with an arm arranged to engage a record on said turntable, a carriage for moving said arm transversely of the record and means for co-operatively controlling the connection between said stylus and the record and said turntable and the driving shaft whereby said stylus head and arm are automatically held clear of the record when the connection and disconnection between said shaft and turntable is being made.
- 10 8. In a phonograph, the combination, a turntable, a driving shaft, a friction wheel splined on said driving shaft having a conical periphery engaging said turntable and means for moving said friction wheel on the spline to vary the speed of said turntable.
- 15 9. In a phonograph, the combination, a turntable, a stylus arm and a feed mechanism for feeding said stylus arm across the turntable, means having a lost motion engagement connecting said feed mechanism and stylus arm and said feed mechanism comprising a sliding carriage and a magnet embodied in said carriage for raising said stylus from the turntable.
- 20 10. In a phonograph, the combination, a turntable and a feed mechanism comprising a sliding carriage, an arm pivotally connected to said carriage and supporting a stylus in engagement with a record on said turntable and means for adjusting the position of said arm horizontally on its pivot to adjust the position of the stylus relative to the sound groove of the record.
- 25 11. In a phonograph, the combination, a plurality of turntables placed one above the other, a shaft for driving said turntables, a record on each turntable, an independent feed mechanism electrically controlled associated with each of said turntables and means adjustable relative to the sound grooves of one turntable record for bringing into operation the feed mechanism of another of said turntables.
- 30 12. In a phonograph, the combination, three or more turntables supporting records placed one above the other, a shaft for driving said turntables, an independent feed mechanism electrically controlled, associated with each of said turntables and means associated with each of said feed mechanisms adjustable relative to the sound grooves on said records for electrically controlling said mechanisms whereby the records on said turntables are automatically played in succession one after the other.
- 35 13. In a phonograph, the combination, a driving shaft, a turntable, a swinging arm carrying said turntable into operative engagement with said driving shaft, a spring for holding said turntable and shaft in engagement and a cam for operating said swinging arm.
- 40 14. In a phonograph, the combination, a driving shaft having a friction wheel thereon, a turntable engaging said wheel and driven by frictional engagement therewith and a pair of cams for changing the frictional engagement for varying the speed of said drive without stopping the turntable.
- 45 15. In a phonograph, the combination, a driving shaft having a conical friction wheel thereon, a turntable engaging said wheel and driven by frictional engagement therewith and a pair of cams for adjusting the position of said conical wheel relative to said turntable.
- 50 16. A feed mechanism for moving a stylus over a phonograph record comprising a shaft, a carriage splined on said shaft, a feed screw, a feed arm pivotally mounted on said carriage and arranged to engage said feed screw and an independent arm carrying the stylus pivotally mounted on said carriage and means pivotally mounted on said carriage operatively connecting said feed arm and said stylus arm. 5
- 55 17. A feed mechanism for moving a stylus over a phonograph record comprising a shaft, a carriage splined on said shaft, a feed screw, a feed arm pivotally mounted on said carriage and arranged to engage said feed screw, an arm carrying a stylus pivotally mounted on said carriage to move independently of said feed arm for engagement with said record and a magnet mounted on said carriage for controlling the operation of said feed arm and said stylus arm. 10
- 60 18. A phonograph mechanism comprising a plurality of turntables for supporting records, a feed screw and a feed mechanism for each turntable, a stylus carried by each of said feed mechanisms in engagement with the records, an arm engaging each of said feed mechanisms with said feed screws and means for simultaneously disengaging the feed mechanisms from the feed screws and restoring said mechanisms to the starting position. 15
- 65 19. A phonograph mechanism, comprising a plurality of turntables for supporting records, a feed screw and a feed mechanism for each turntable, a stylus carried by each of said feed mechanisms in engagement with the records, an arm engaging each of said feed mechanisms with said feed screws, horizontal bars arranged to engage said arms and disengage them from the feed screw and means for simultaneously moving said horizontal bars. 20
- 70 20. A phonograph mechanism, comprising a plurality of turntables for supporting records, a feed screw and a feed mechanism for each turntable, a stylus carried by each of said feed mechanisms in engagement with the records, horizontal sliding bars arranged to engage said mechanism, a pivoted mounting for said bars and means for moving said bars on said mounting to engage said mechanism. 25
- 75 21. A feed mechanism for feeding a stylus across a record on a phonograph turntable, comprising a sliding carriage with a feed screw, an arm carrying the stylus pivoted to said carriage to swing horizontally, a spring moving said arm in one direction and means for adjusting the position of said arm against said spring. 30
- 80 22. A feed mechanism for feeding a stylus on a phonograph record comprising a sliding carriage, a feed screw, means connecting said carriage with said feed screw, a magnet controlling said means, an arm carrying a stylus to engage the record mounted on said carriage, a lever operated by the movement of said carriage, a plate pivotally adjusted relative to said lever, said lever and plate operating a circuit controller controlling said magnet in a predetermined position of said carriage. 35
- 85 23. A phonograph mechanism comprising a plurality of turntables continuously rotating, means for stopping one turntable without stopping the others, a feed mechanism with a carriage for each turntable arranged to carry the stylus in engagement with the records on the 40

turntables, electrical means mounted on said carriage controlling the operation of each carriage and means controlled by one carriage in a predetermined position for stopping said carriage 5 and for starting the feed mechanism of another turntable.

24. A phonograph mechanism comprising a plurality of turntables continuously rotating, means for stopping one turntable without stopping the others, a feed mechanism for each turntable arranged to carry the stylus in engagement with the records on the turntables, means associated with the turntable mechanism for operating the feed mechanism and electrically controlled means mounted on said carriage for selectively connecting said feed mechanism with said operating means.

25. In a phonograph, the combination, a rotating turntable, a feed mechanism for feeding a stylus across the turntable, and a magnet controlling the movement of said feed mechanism, the circuit of said magnet being controlled by the angular position of said turntable.

26. In a phonograph, the combination, a turntable, a feed mechanism for feeding a stylus across the turntable, a magnet controlling the movement of said feed mechanism, a holding circuit controlling said magnet and means controlling said holding circuit by the initial movement of said mechanism.

27. In a phonograph, the combination, a turntable, a feed mechanism for feeding a stylus across the turntable, and a magnet controlling the movement of said feed mechanism, said magnet having a pick up circuit and a holding circuit, said circuits controlled by said feed mechanism.

28. In a phonograph, the combination, a turntable, a feed mechanism comprising a feed arm and a feed screw for feeding a stylus across the turntable, a magnet controlling the engagement of said feed arm and feed screw and means controlling the circuit of said magnet by the movement of said turntable.

29. In a phonograph, the combination, a turntable with a record thereon, means for driving said turntable, a stylus arm with a stylus arranged to engage and move over the sound grooves of the record, a magnet controlling said stylus arm to engage and disengage the stylus and the record, and a pick up circuit and a holding circuit energized at different times and energizing said magnet whereby repeating operations of the stylus arm are prevented.

30. In a phonograph, the combination, a turntable with a record thereon, means for driving said turntable, a stylus arm with a stylus arranged to engage and move over the sound grooves of the record, a magnet controlling said stylus arm to engage and disengage the stylus and the record, a pick up circuit and a holding circuit energizing said magnet and said magnet itself controlling said holding circuit, said circuits being controlled by the movement of the stylus arm whereby repeating operations of the stylus arm are prevented.

31. In a phonograph, the combination, a turntable, a feed mechanism, a feed arm having a stylus carried by said mechanism across the turntable, a magnet having a pick up circuit and a holding circuit controlling the engagement of said stylus with said record and means controlled by the rotation of said turntable for controlling one of the circuits of said magnet and means controlled by the movement of said feed arm for controlling the other circuit of said magnet.

32. In a phonograph, the combination, a turntable, a feed mechanism, a feed arm engaging a feed screw and a stylus arm carrying a stylus across the turntable, said arms being pivotally mounted independently in said mechanism and a lost motion connection connecting said feed arm with said stylus arm. 5

33. In a phonograph, the combination, a turntable, a feed mechanism, a feed arm engaging a feed screw and a stylus arm carrying a stylus 10 across the turntable, said arms being pivotally mounted independently in said mechanism with their pivotal axis in alignment and means connecting said feed arm and stylus arm whereby disengaging said feed arm from said feed screw 15 raises said stylus arm from the turntable.

34. In a phonograph, the combination, a turntable, a feed mechanism moving on a fixed slide comprising a feed screw on one side of said slide, a feed arm engaging said screw, an independent 20 stylus arm on the other side of said slide, and links connecting said feed arm and stylus arm whereby raising said feed arm to disengage it from said screw raises said stylus arm from the turntable. 25

35. In a phonograph, the combination, a plurality of turntables having records thereon, means for continuously rotating said turntables, and means for stopping any turntable without stopping the rotation of the other turntables, a feed 30 mechanism for feeding a stylus across the record on each turntable, a magnet controlling each of said feed mechanisms and means operated by the completion of the first record for automatically starting the feed mechanism of the second turntable and for automatically starting the feed 35 mechanism of the third turntable by the second turntable.

36. In a phonograph, the combination, a plurality of turntables having records thereon, means 40 for continuously rotating said turntables, a feed mechanism for feeding a stylus across the record on each turntable, a magnet mounted to move with said feed mechanism controlling each of said feed mechanisms and means operated upon the 45 completion of one record for automatically starting the feed mechanism of the next record and at the same time returning the feed mechanism of the completed record to the starting position.

37. In a phonograph, the combination, a plurality of turntables having records thereon, means for continuously rotating said turntables, a feed mechanism for feeding a stylus across the record on each turntable, a magnet controlling each of 55 said feed mechanisms and an electrically operated stepping device for selectively operating said feed mechanisms one after the other in succession.

38. In a phonograph, the combination, a plurality of turntables having records thereon, means for continuously rotating said turntables, a feed 60 mechanism for feeding a stylus across the record on each turntable, a magnet controlling each of said feed mechanisms, a stepping device for selectively operating said feed mechanisms and means for electrically operating said stepping device. 65

39. In a phonograph, the combination, a plurality of turntables having records thereon, means for continuously rotating said turntables, a feed mechanism for feeding a stylus across the record 70 on each turntable, a magnet controlling each of said feed mechanisms, a stepping device for selectively operating said feed mechanisms and means controlled by said feed mechanism for electrically operating said stepping device. 75

40. A phonograph mechanism comprising a turntable supporting a record, a stylus arm supporting a stylus head arranged to carry a stylus in engagement with the record and capable of being disengaged from the record, means for moving said arm to the disengaging position and a magnet having a holding circuit controlling said means, said circuit controlled by said turntable.
41. A phonograph mechanism comprising a plurality of turntables supporting records, a stylus head for each record supporting a stylus in engagement with the record and mounted to follow the spiral sound grooves of the record, means supporting each stylus head and capable of being moved to disengage the stylus from the record, a magnet for moving each of said supporting means, a holding circuit for energizing each magnet controlled by the magnet itself and means for interrupting said holding circuit for one record when the stylus head on another record has reached a predetermined position.
42. A phonograph mechanism comprising a turntable supporting a record, a stylus head supporting a stylus in engagement with the record, means supporting said stylus head and capable of being moved to disengage the stylus from the record, a magnet controlled by a holding circuit and by a pick up circuit for moving said supporting means and means for closing said holding circuit in one position of the stylus head and for opening said circuit in another position of the stylus head and means for energizing said pick up circuit by said phonograph mechanism.
43. A phonograph mechanism comprising a turntable supporting a record, a stylus head supporting a stylus in engagement with the record, means supporting said stylus head and capable of being moved to disengage the stylus from the record, a magnet controlled by a holding circuit for moving said supporting means and means for opening said holding circuit when the stylus has completed its movement over the record to prevent the stylus repeating its movement.
44. In a phonograph, the combination, a plurality of turntables supporting records, means for simultaneously driving said turntables, means for removing any of said turntables from said drive without stopping the other turntables, a stylus arm supporting a stylus for each record, a magnet for each stylus arm controlling its engagement with the record and means controlling said magnets whereby the records on said turntables are automatically played in succession.
45. In a phonograph, the combination, a plurality of turntables supporting records, means for simultaneously driving said turntables, a stylus arm supporting a stylus for each record, a magnet for each stylus arm controlling its engagement with the record and a remotely operated stepping device making a plurality of steps controlling the circuits of said magnets to release one stylus arm for engagement with the record for each step of said device.
46. In a phonograph, the combination, a plurality of turntables supporting records, a stylus arm supporting a stylus for each record, a magnet for each stylus arm mounted to move with said arm controlling its engagement with the record, means for simultaneously driving said turntables, means for removing any of said turntables from the drive without stopping the other turntables, and remotely located means controlling the circuits of said magnets.
47. In a phonograph, the combination, a plurality of turntables supporting records, means for simultaneously driving said turntables, a stylus arm supporting a stylus for each record, a magnet for each stylus arm controlling its engagement with the record and means for removing any of said turntables from the drive without stopping the other turntables, a magnet for each stylus arm mounted to move with said arm controlling its engagement with the record, a pair of guides, means connecting said wheel with said guides and moving on said guides for sliding

said wheel on said shaft and means for operating said connecting means to vary the speed of said turntable.

56. In a phonograph mechanism, a turntable for playing disc type records, a constant speed drive shaft, a conical drive wheel splined on said shaft, a turntable member frictionally engaging

said wheel, a spring for securing said engagement, a pair of guides, means connecting said wheel with said guides, and rotary means associated with said guides for shifting the position of said wheel relative to said member to vary the speed of said turntable. 5

MATTHEW H. LOUGHRIDGE.
